(57) **CLAIM**

The ornamental design for a combined massage and exercise device, as shown and described.

DESCRIPTION

FIG. 1 is a front view of a combined massage and exercise device with an inner roller thereof shown fully inserted into an outer roller thereof according to the design;

FIG. 2 is a rear view thereof;

FIG. 3 is a right side end view thereof;

FIG. 4 is a left side end view thereof;

FIG. 5 is a front perspective view thereof;

FIG. 6 is a rear perspective view thereof;

FIG. 7 is a front perspective view thereof shown in an environment of use and at a reduced scale;

FIG. 8 is a rear perspective view thereof with the inner roller thereof shown partially removed from the outer roller thereof;

FIG. 9 is a front view of the outer roller of the combined massage and exercise device of FIG. 1;

FIG. 10 is a rear view thereof;

FIG. 11 is a right side end view thereof;

FIG. 12 is a left side end view thereof;

FIG. 13 is a front perspective view thereof;

FIG. 14 is a rear perspective view thereof;

FIG. 15 is a front perspective view thereof shown in an environment of use and at a reduced scale;

FIG. 16 is a front view of the inner roller of the combined massage and exercise device of FIG. 1;

FIG. 17 is a rear view thereof;

FIG. 18 is a right side end view thereof;

FIG. 19 is a left side end view thereof;

FIG. 20 is a front perspective view thereof;

FIG. 21 is a rear perspective view thereof; and,

FIG. 22 is a front perspective view thereof shown in an environment of use and at a reduced scale.

(Continued)

The broken line showing of the human figure in FIGS. 7, 15 and 22 is for the purpose of illustrating portions of the environmental structure and forms no part of the claimed design.
